UNITED STATES PATENT OFFICE

2,089,826

ELECTRIC HEATING SYSTEM CONTROL

Lewis L. Cunningham, Minneapolis, Minn., assignor to Minneapolis-Honeywell Regulator Company, Minneapolis, Minn., a corporation of Delaware

Original application May 27, 1933, Serial No. 673,236. Divided and this application July 19, 1935, Serial No. 32,223

7 Claims. (Cl. 219—20)

The present invention relates to the control of temperature changing systems and particularly those in which heat is generated electrically as by passing current through suitable resistors. 5 The object of the invention is the provision of a temperature changing system in which the flow of current to an electrical temperature changing means, such as a heating resistor or resistors, is controlled by an induction voltage regulator that is in turn controlled by a novel 10 electrically balanced proportioning or graduated control apparatus.

For a more complete understanding of the invention, reference may be had to the following 15 detailed description and accompanying single drawing which is a diagrammatic showing of one form of the invention.

This application is a division of my copending 20 application Serial No. 673,236, filed May 27, 1933 and entitled "Remote control systems".

Referring to the single drawing, there is shown 25 a control potentiometer comprising a control resistance 10 which is contacted by a movable member 11 herein shown as actuated by a bimetallic element 12 which may respond, for instance, to the temperature of an industrial furnace. In actual commercial construction, the movable member 11 is operated by any of the well-known mechanisms controlled by a thermocouple such as a Leeds and Northrup controller. 30 The system of the present invention further includes a pair of solenoid coils 13 and 14 which control a plunger 15 that is connected to a flexible switch arm 16 by means of a light spring 17. One end of control resistance 10 is connected 35 to solenoid coil 13 through a protective resistance 18 by means of wires 19 and 20. The other end of control resistance 10 is connected to one end of solenoid coil 14 through a protective resistance 21 by means of wires 22 and 23. Line wires 24 and 25 supply power to the primary 26 of a step-down transformer having a low voltage secondary 27. Wire 20, and therefore one end of solenoid coil 13, is connected to one side of secondary 27 by means of wires 28 and 29. In like manner, 40 wire 23, and therefore one end of solenoid coil 14, is connected to the other side of secondary 27 by means of wires 30 and 31.

The flexible switch arm 16 carries movable contacts 32 and 33 which are adapted to respectively engage stationary contacts 34 and 35. The system further includes a balanced relay having windings 36 and 37, the junction of which is connected to flexible switch arm 16 through a protective resistance 38 by means of wires 39

and 40. The other end of relay winding 36 is connected to stationary contact 35 by wires 51 and 52 and is connected to one side of secondary 27 by wires 51, 53, and 31. The outer end of relay winding 37 is connected to stationary contact 34 by wires 54 and 55 and is connected to the other side of secondary 27 by wires 54, 56 and 29. 5

Relay windings 36 and 37 control a plunger 57 which is connected to a relay switch arm 58 through a light spring 59. Relay switch arm 58 carries movable contacts 60 and 61 which are respectively cooperable with stationary contacts 62 and 63. 10

The switch arm 58 and associated contacts 15 control first and second relays. The first relay comprises a relay coil 64 which controls an armature 65 to which are secured switch arms 66 and 67 that are adapted to respectively engage contacts 68 and 69 upon energization of relay coil 20 64. The second relay comprises a relay coil 70 which controls an armature 71 to which are secured switch arms 72 and 73 that are adapted to respectively engage contacts 74 and 75 upon energization of relay coil 70. 25

The first and second relays control an induction voltage regulator which comprises a three-phase motor 76 which operates a movable element or armature 77. The induction voltage regulator includes windings 78 and 79; the latter of which is positioned by movable element or armature 77 as is well-known by those skilled in the art. 30

A balancing potentiometer is comprised by a balancing resistance 80 and a balancing contact finger 81 which is actuated by a link 82 that is connected to movable element or armature 77 for reciprocation thereby. One end of balancing resistance 80 is connected to one end of control resistance 10 and to wire 19 by a wire 83. The other end of balancing resistance 80 is connected to the other end of control resistance 10 and to wire 22 by a wire 84. Wires 85, 86, and 87 interconnect balancing contact finger 81, movable member 11, and the junction of solenoid coils 13 and 14. 40

The induction voltage regulator controls the voltage impressed upon an electric heating means, herein shown as a single electrical resistance 88, which may heat an electric furnace, the 50 temperature of which is to be controlled by the present system due to the response of bimetallic element 12.

A three-phase source of power is indicated by line wires 89, 90 and 91. Line 89 is connected 55

to the junction of coils 78 and 79 by a wire 92. The other end of winding 78 is connected to heating resistance 88 by a wire 93. The other end of heating resistance 88 is connected to the lower 5 end of winding 79 and to line 90 by wires 94, 95, and 96. The remaining circuit connections will be described under the heading "Operation".

A single phase voltage induction regulator and a single heater 88 have been shown for simplicity. In actual practice a three-phase voltage induction regulator and a three-phase heater would be used as will be appreciated by those skilled in the art.

15

Operation

With the parts in the position shown wherein movable member 11 is contacting the center of control resistance 10 and balancing contact finger 81 is contacting the center of balancing resistance 80, the voltage drops across solenoid coils 13 and 14 are equal. Contacts 32 and 33 are therefore out of engagement with contacts 34 and 35 with the result that relay windings 36 and 37 are equally energized since they are connected in series across secondary 27. Contacts 60 and 61 are therefore out of engagement with contacts 62 and 63. Relay coils 64 and 70 are both de-energized and heating resistance 88 is supplying just enough heat to maintain the furnace temperature at the desired point.

Now if the furnace temperature should rise, bimetallic element 12 in responding to such a rise in furnace temperature moves movable member 11 along control resistance 10 toward the left hand end thereof, thereby increasing the voltage drop across solenoid coil 14 and decreasing the voltage drop across solenoid coil 13, whereby plunger 15 moves to the right and causes contact 32 to engage contact 34. Engagement of contact 32 with contact 34 places protective resistance 38 in parallel with relay winding 37. The full current flow through protective resistance 38 and relay winding 37 now flows through relay winding 36 causing plunger 45 57 to be moved to the left and bring contact 61 into engagement with contact 63.

Relay coil 64 is thereby energized by a circuit which is as follows: line 24, wire 97, switch arm 58, contacts 61 and 63, wire 98, relay coil 64, 50 wire 99 and wire 100 to line 25. Armature 65 is attracted and moves switch arms 66 and 67 into engagement with contacts 68 and 69. Two circuits are thus established to three-phase motor 76. The first circuit is as follows: line 89, wire 101, motor 76, wire 102, wire 103, contact 68, switch arm 66, wire 104, and wire 105 to line 90. The second circuit is as follows: line 89, wire 101, motor 76, wire 106, wire 107, contact 69, switch arm 67, wire 108, and wire 109 to line 91. 60 Motor 76 will now begin to rotate movable element or armature 77 in a counter-clockwise direction through suitable reduction gearing generally indicated at 110. Such movement of movable element 77 slowly moves winding 79 in 65 respect to winding 78, as is well-known to those skilled in the art, with the result that the voltage impressed across heating resistance 88 is reduced so as to reduce the amount of heat furnished by heating resistance 88. Link 82 will 70 be moved to the right and carries with it balancing contact finger 81 which rebalances the voltage drops across solenoid coils 13 and 14 when balancing contact finger 81 has been moved to the proper position along balancing resistance 80.

Rebalancing of the voltage drops across solenoid coils 13 and 14 causes plunger 15 to move to the left until it reaches its normal central position. This movement of plunger 15 disengages contact 32 from contact 34 whereby the circuit through protective resistance 38 is interrupted. Interruption of the circuit through resistance 38 rebalances the voltage drops across and the current flows through relay windings 36 and 37 whereupon plunger 57 is moved to the right until its normal central position is reached. Contact 61 is thereby moved out of engagement with contact 63 to deenergize relay coil 64, whereupon armature 65 moves by gravity to the position shown thereby interrupting the two circuits to 15 three-phase motor 76.

The parts will remain in their new positions until there is a further change in furnace temperature. If the furnace temperature should again rise, movable member 11 will be moved nearer to the left-hand end of control resistance 10 and the above described sequence of operations will be repeated. When the furnace temperature falls, bimetallic element 12 moves movable member 11 along control resistance 10 25 towards the right-hand end thereof. This action increases the voltage drop across solenoid coil 13 and decreases the voltage drop across solenoid coil 14 which results in movement of plunger 15 to the left. Contact 33 is thereby moved into 30 engagement with contact 35 whereupon protective resistance 38 is placed in parallel with relay winding 36 and the current flow through protective resistance 38 and relay winding 36 all traverses relay winding 31. Plunger 57 is therefore 35 moved to the right causing contact 60 to engage contact 62.

Engagement of contact 60 with contact 62 energizes relay coil 70 by a circuit which is as follows: line 24, wire 97, relay switch arm 58, 40 contacts 60 and 62, wire 111, relay coil 70, wire 112, and wire 100 to line 25. Energization of relay coil 70 attracts armature 71 which in turn moves switch arms 72 and 73, respectively, into engagement with contacts 74 and 75. Two energizing circuits are therefore established for three-phase motor 76 which circuits rotate said motor 76 in a direction opposite to that to which it was formerly rotated. The first of these circuits is as follows: line 89, wire 101, motor 76, wire 102, 50 wire 113, contact 75, switch arm 73, wire 114, and wire 109 to line 91. The second new energizing circuit for motor 76 is as follows: line 89, wire 101, motor 76, wire 106, wire 115, contact 74, switch arm 72, wire 116, and wire 105 to 55 line 90.

Movable element or armature 77 is therefore rotated in a clockwise direction and moves balancing contact finger 81 along balancing resistance 80 toward the left end thereof by means of 60 link 82 and also moves winding 79 in respect to winding 78 in a direction to increase the voltage impressed across heating resistance 88. This action will continue until the amount of heat delivered by heating resistance 88 is sufficient 65 to prevent further drop in furnace temperature and the furnace temperature levels off at some constant value. At this time balancing contact finger 81 will be in contact with that portion of balancing resistance 80 which rebalances the 70 voltage drops across solenoid coils 13 and 14.

Plunger 15 is thereupon moved to its normal central position to interrupt the circuit through protective resistance 38 by separating contacts 33 and 35. The current flows through relay 75

windings 36 and 37 are thereby equalized and plunger 57 returns to its normal central position to interrupt the circuit through relay coil 70 by separating contacts 60 and 62. Armature 5 71 moves under the influence of gravity to the position shown and interrupts the two above described energizing circuits for three-phase motor 76.

In this manner, the heating effect of heating 10 resistance 88 is decreased or increased as the furnace temperature rises above or falls below normal and this decrease or increase in the heating effect of heating resistance 88 is proportional to the departure of the furnace temperature from 15 the desired normal. This is accomplished by automatically operating the movable element of a three-phase induction voltage regulator. The temperature range within which the temperature is thus allowed to fluctuate may be predetermined, within reasonable limits, by so adjusting 20 or constructing the furnace temperature responsive mechanism that the movable member 11 moves from one end of control resistance 10 to the other end thereof when the furnace temperature changes from one of its predetermined 25 limits to the other of its predetermined limits.

From the foregoing description of the invention, it will be apparent that I have provided a novel temperature control system in which 30 many changes and rearrangements may be made without departing from the spirit thereof, wherefore I am to be limited only by the scope of the appended claims.

I claim:

35 1. In an electrically controlled heating system, in combination, electrical heating means which varies its heating effect in accordance with the voltage impressed thereon, an induction voltage regulator in control of the voltage impressed upon said heating means, said induction voltage regulator including a movable element which causes variation in the voltage impressed upon the heating means when said element is moved, three-phase reversible motor means in control 40 of said movable element to position the same, first and second relays, two circuits for said motor means controlled by each of said relays, one set of said circuits operating said motor means in one direction and the other set operating the 45 motor means in the other direction, double circuit switching means in control of said relays to selectively energize the same, or deenergize both of them, a condition responsive controller, and means including connections between said controller, switching means and movable element by which movement of said controller to a new position operates said switching means to energize one or the other of said relays to cause movement of said movable element in a direction to 50 deenergize such relay.

2. In an electrically controlled heating system, in combination, electrical heating means which varies its heating effect in accordance with the voltage impressed thereon, an induction voltage 55 regulator in control of the voltage impressed upon said heating means, said induction voltage regulator including an element which varies the voltage impressed upon the heating means when moved, electric motor means to position said movable element, switching means in control of the energization of said motor means, a balancing potentiometer mechanically connected to said movable element, a control potentiometer, electromagnetic means to operate said switching means, and electrical connections between said

electromagnetic means and potentiometers by which the energization of said electromagnetic means is controlled by the positions of said potentiometers.

3. In an electrically controlled heating system, in combination, electrical heating means which varies its heating effect in accordance with the voltage impressed thereon, an induction voltage regulator in control of the voltage impressed upon said heating means, said induction voltage regulator including an element which varies the voltage impressed upon the heating means when moved, three-phase reversible electric motor means to position said movable element, first and second relays, two energizing circuits for said motor means arranged to be completed by each of said relays, one set of said circuits operating said motor means in one direction and the other set operating the motor means in the other direction, double circuit switching means in control of the energization of said relays to selectively energize the same or deenergize both of them, a balancing potentiometer positioned by said movable element, a control potentiometer, electromagnetic means to operate said switching means and electrical connections between said potentiometers and electromagnetic means by which the energization of said electromagnetic means is varied upon movement of either of said potentiometers.

4. In an electrically controlled temperature control system, in combination, electrical temperature changing means of the type which varies its temperature changing effect upon variation of the voltage impressed thereon, a voltage regulator including a movable element operative to change the voltage impressed upon said temperature changing means upon movement of said movable element, a source of power, a pair of electromagnetic coils connected in series across said source of power, a temperature responsive control potentiometer and a balancing potentiometer each having its resistance connected in parallel with the series-connected electromagnetic coils, connections between the junction of said electromagnetic coils and the contact elements of said potentiometers, resistance means associated with said potentiometers and electromagnetic coils operative to prevent complete short-circuiting of either electromagnetic coil upon movement of any 50 potentiometer to an extreme position, a mechanical connection between said movable element and said balancing potentiometer, motor means in control of said movable element, and switching means controlled by the conjoint action of said 55 electromagnetic coils in control of said motor means.

5. In an electrically controlled temperature control system, in combination, electrical temperature changing means of the type which varies its temperature changing effect upon variation of the voltage impressed thereon, a voltage regulator including a movable element operative to change the voltage impressed upon said temperature changing means upon movement of said movable 60 element, a source of power, a pair of electromagnetic coils connected in series across said source of power, a temperature responsive control potentiometer and a balancing potentiometer each having its resistance connected in parallel 65 with the series connected electromagnetic coils, connections between the junction of said electromagnetic coils and the contact elements of said potentiometers, resistance means associated with said potentiometers and electromagnetic coils 70 75

- operative to prevent complete short-circuiting of either electromagnetic coil upon movement of any potentiometer to an extreme position, a mechanical connection between said movable element and said balancing potentiometer, motor means in control of said movable element, relay means including a pair of relay coils connected in series across a source of power in control of said motor means, and switching means controlled by the cooperative action of said electromagnetic coils operative to shunt one or the other of said relay coils whereby to render the other relay coil operative to control said motor means.
6. In an electrically controlled temperature control system, in combination, electrical temperature changing means of the type which varies its temperature changing effect upon variation of the voltage impressed thereon, a voltage regulator including a movable element operative to change the voltage impressed upon said temperature changing means upon movement of said movable element, a source of power, a pair of electromagnetic coils connected in series across said source of power, a temperature responsive control potentiometer and a balancing potentiometer each having its resistance connected in parallel with the series connected electromagnetic coils, connections between the junction of said electromagnetic coils and the contact elements of said potentiometers, resistance means associated with said potentiometers and electromagnetic coils operative to prevent complete short-circuiting of either electromagnetic coil upon movement of any potentiometer to an extreme position, a mechanical connection between said movable element and said balancing potentiometer, three phase motor means in control of said movable element, a pair of relays, two circuits controlled by each relay and connected to said motor means, one set of circuits being operable to move said motor means in one direction and the other set of circuits being operable to move said motor means in the other direction, balanced relay means in control of said relays comprising a pair of relay coils connected in series across said source of power, and double circuit switching means operative to selectively shunt one or the other of said relay coils controlled by the conjoint action of said electromagnetic coils.

and the other set of circuits being operable to move said motor means in the other direction, and switching means in control of said relays controlled by the conjoint action of said electromagnetic coils.

7. In an electrically controlled temperature control system, in combination, electrical temperature changing means of the type which varies its temperature changing effect upon variation of the voltage impressed thereon, a voltage regulator including a movable element operative to change the voltage impressed upon said temperature changing means upon movement of said movable element, a source of power, a pair of electromagnetic coils connected in series across said source of power, a temperature responsive control potentiometer and a balancing potentiometer each having its resistance connected in parallel with the series-connected electromagnetic coils, connections between the junction of said electromagnetic coils and the contact elements of said potentiometers, resistance means associated with said potentiometers and electromagnetic coils operative to prevent complete short-circuiting of either electromagnetic coil upon movement of any potentiometer to an extreme position, three-phase motor means in control of said movable element and balancing potentiometer, a pair of relays, two circuits controlled by each relay and connected to said motor means, one set of circuits being operable to move said motor means in one direction and the other set of circuits being operable to move said motor means in the other direction, balanced relay means in control of said relays comprising a pair of relay coils connected in series across said source of power, and double circuit switching means operative to selectively shunt one or the other of said relay coils controlled by the conjoint action of said electromagnetic coils.

LEWIS L. CUNNINGHAM.
